UNITED STATES PATENT OFFICE

112,919

DESIGN FOR A COMBINATION HOLDER FOR ASHTRAY AND MATCH PACKET

Louis B. Ankovitz, Brooklyn, N. Y.

Application April 1, 1938, Serial No. 76,221

Term of patent 7 years

To all whom it may concern:

Be it known that I, Louis B. Ankovitz, a citizen of the United States, residing at Brooklyn, in the county of Kings and State of New York, have invented a new, original, and ornamental Design for a Combination Holder for Ashtray and Match Packet, of which the following is a specification, reference being had to the accompanying drawing, forming part thereof,

In the drawing:

The figure is a perspective view of a combination holder for ashtray and match packet, showing my new design.

I claim:

The ornamental design for a combination holder for ashtray and match packet, as shown.

LOUIS B. ANKOVITZ.
